UNITED STATES PATENT OFFICE.

STEPHEN A. HASBROUCK, OF NEW HAVEN, CONNECTICUT.

IGNITION MEANS AND METHOD.

Application filed October 31, 1921. Serial No. 511,818.

To all whom it may concern:

Be it known that I, STEPHEN A. HASBROUCK, a citizen of the United States, residing at New Haven, in the county of New Haven and State of Connecticut, have invented certain new and useful Improvements in Ignition Means and Methods, of which the following is a specification, reference being had therein to the accompanying drawings.

This invention relates to new and useful means and method for igniting the fuel charge of an internal combustion engine and it is the principal object thereof to provide both a method and means for the initial starting of such engine when cold or with a liquid as distinguished from a vaporized fuel.

Among other aims and objects of the invention may be recited the provision of a device embodying the features of the method mentioned with a view to simplicity and compactness, the cost of production small and efficiency and operation high.

The method and one of the many means by which the same may be performed will be apparent from an inspection of the accompanying drawings in connection with the description hereinafter contained and wherein a preferred embodiment of the invention is disclosed for the purpose of imparting an understanding of the same.

In the drawings,

Figure 1 is a sectional elevation of the upper portion of the cylinder of an internal combustion engine with one form of my invention connected therewith; and

Figure 2 is a similar view showing another of such forms.

It is difficult with the devices heretofore used to start an internal combustion engine when the cylinder and its operating parts are cold, which difficulty is very greatly increased if the fuel is in a liquid form rather than a vaporized form.

With my improved method I install in the cylinder a device that produces a flame as distinguished from the spark of the ordinary spark plug, which flame is of sufficient magnitude and burns for a sufficient length of time to make positive the explosion of the fuel irrespective of the temperature of the cylinder.

Having more particular reference to the drawings and in connection with which like reference characters refer to corresponding

parts, 10 designates the cylinder of an explosive engine, 11 the piston movable therein, 12 the spray nozzle through which the fluid is admitted into the cylinder from a conductor pipe 13.

In Figure 1 the head of the cylinder is solid while in Figure 2 the head 14 is separate and is secured thereto in any desired manner.

All of the mechanism above described is constructed and operates in a well known manner.

In Figure 1, 15 designates the spark plug, 16 the primary electrode forming a part thereof, 17 the secondary electrode which is preferably formed so as to provide a cage 18 inclosing a wick 19 of non-combustible material, such as asbestos or the like.

Connected with the cylinder directly in line with the cage 18 is a priming cup 20 which contains a small quantity of the fuel, and having a valve 21 connected therewith.

In starting the engine the valve 21 is manipulated so that a small quantity of the fuel is discharged from the primary cup 20 through the port 22 and drops onto the cage 18 and which moistens the latter. The current is then turned onto the spark plug in the usual manner and the spark formed across the gap between the primary electrode 16 and the secondary electrode 17 ignites the fuel in the wick 19, thus producing a flame which readily ignites the fuel projected into the cylinder from the spray nozzle 12, thus positively causing the engine to start.

The necessary air for combustion is supplied during each cycle of the piston 11 as is usual. If perchance, the flame is extinguished by the explosion, it is relighted by the spark and it will burn until the fuel in the wick has been consumed.

After the wick is primed, the valve 21 is manipulated so as to shut off the discharge of priming fuel.

The structure shown in Figure 1 differs from that shown in Figure 2 in that the electrode 23 is fixed in the cylinder 10 and surrounded by a cage or basket 24 within which is the wick 25 of non-combustible material, the priming cup 20 being located in line with the basket 24 from which priming fuel is supplied thereto.

Many other means may be substituted for those shown herein and accomplish the same results, therefore in the practice of my in-

vention I desire it to be understood that I do not limit myself to the exact construction herein shown and described but claim all that falls fairly within the spirit and scope 5 of the appended claims.

What I claim as new and desire to secure by Letters Patent, is:

1. The method of operating an internal combustion engine, which consists in admitting a limited quantity of priming fuel into 10 the cylinder and there igniting the same to form a flame that will ignite the fuel admitted thereto to operate the engine.
2. In an internal combustion engine, a cylinder, spark mechanism, a wick adjacent thereto, means for admitting fuel to said cylinder, and independent means for supplying a limited quantity of priming fuel to said wick.
3. In an internal combustion engine, a cylinder, spark mechanism, a cage or basket inclosing a wick of non-combustible material, means for admitting fuel to said cylinder,

der, and independent means in line with said wick for admitting a limited quantity of fuel thereto.

4. In an internal combustion engine, a cylinder, means for admitting fuel to said cylinder, independent means adjacent thereto for admitting a limited quantity of priming fuel into said cylinder, a sparking mechanism in said cylinder, and a wick of non-combustible material within said cylinder opposite the point of admission of said priming fuel thereto.

5. In an internal combustion engine, a cylinder, a spark mechanism having a primary electrode and a secondary electrode, the latter having a wick connected therewith, means for admitting fuel to said cylinder, and independent means for supplying a limited quantity of priming fuel to said wick.

In testimony whereof, I have hereunto affixed my signature.

STEPHEN A. HASBROUCK.
